Primary Examiner — Kimberly Barnes*(74) Attorney, Agent, or Firm* — Abel Sehillinser, LLP;
Thomas H. Osborn(57) **CLAIM**

The ornamental design for a siding panel, as shown and described.

DESCRIPTION

FIG. 1 is a top front isometric view of a siding panel showing our new design.

FIG. 2 is a front view of FIG. 1.

FIG. 3 is a rear view of FIG. 1.

FIG. 4 is a right side view of FIG. 1.

FIG. 5 is a left side view of FIG. 1.

FIG. 6 is a top view of FIG. 1; and,

FIG. 7 is a bottom view of FIG. 1.

The broken lines in the drawings depict portions of the siding panel that form no part of the claimed design.
